UNITED STATES PATENT OFFICE.

EDWARD M. LOFTUS, OF NEW YORK, N. Y.

DESIGN FOR AN ARTICLE OF MANUFACTURE.

54,757.

Specification for Design.

Patented Mar. 23, 1920.

Application filed October 3, 1919. Serial No. 328,292. Term of patent 3½ years.

To all whom it may concern:

Be it known that I, EDWARD M. LOFTUS, a citizen of the United States, and a resident of the city of New York, borough of Manhattan, in the county of New York and State of New York, United States of America, have invented a new, original, and ornamental Design for an Article of Manufacture, of which the following is a specification, reference being had to the accompanying drawing, forming part thereof, in which the figure is a front view of a table-cover embodying my new design.

The design consists of two irregular lines having the representation of flowers thereon arranged in clusters and separately with branches and leaves.

The design is applied to pillow covers, scarfs, bolster covers, bedspreads, and articles of similar nature.

I claim:

The ornamental design for an article of manufacture substantially as shown and described.

EDWARD M. LOFTUS.
